Primary Examiner — Paula Allen Greene(74) *Attorney, Agent, or Firm* — Wood Herron & Evans LLP(57) **CLAIM**

The ornamental design for a cremation urn, as shown and described.

DESCRIPTION

FIG. 1 is a front view of our new, original and ornamental design for a cremation urn, the back view, left side view, and right side view thereof being at least substantially identical thereto in that the pattern of the surface ornamentation repeats around the circumference of the cremation urn.

FIG. 2 is a top view thereof.

FIG. 3 is a front view of another embodiment of our new, original and ornamental design for a cremation urn, the back view, left side view, and right side view thereof being at least substantially identical thereto in that the pattern of the surface ornamentation repeats around the circumference of the cremation urn; and,

FIG. 4 is a top view thereof.

The unshown portions of the article form no part of the claimed design.
